UNITED STATES PATENT OFFICE.

CORNELIUS HENRY DE BERNARDI, OF WEST HOBOKEN, NEW JERSEY.

VANITY CASE.

Application filed December 6, 1923. Serial No. 679,038.

To all whom it may concern:

Be it known that I, CORNELIUS HENRY DE BERNARDI, a citizen of the United States, and a resident of West Hoboken, in the 5 county of Hudson and State of New Jersey, have invented a new and Improved Vanity Case, of which the following is a full, clear, and exact description.

This invention relates to vanity cases and 10 has for an object to provide an improved structure wherein cosmetics are arranged in a convenient manner and means are provided for supporting desirable articles other than cosmetics.

15 Another object of the invention is to provide a vanity case in which cosmetics are arranged in one section or part and cigarettes or other desirable articles arranged in another part, the various parts being so 20 positioned that they will not interfere.

A still further object of the invention is to provide a vanity case in which a cigarette receiving drawer is provided, with the drawer and the other parts so arranged 25 that the cigarettes are not brought to view when the case is opened while all of the cosmetics are exposed.

In the accompanying drawing—

Figure 1 is a perspective view of a case, 30 disclosing an embodiment of the invention, the same being shown open and filled.

Figure 2 is a transverse sectional view through the case shown in Figure 1.

Figure 3 is a top plan view of the case 35 shown in Figure 1, the same being shown open and also empty.

Referring to the accompanying drawing by numerals, 1 indicates a container which is shown substantially rectangular but may 40 be of any desired shape. This container is cut away at 2 for providing a front opening for accommodating the drawer 3, which drawer extends to the vertical partition 4, which partition is connected with a false 45 bottom 5. The drawer 3 is intended to carry any suitable article, as for instance, cigarettes, while the main part of the container 1 is intended to carry some form of cosmetics. By providing the wall 4, as

50 shown in Figure 2, a deep compartment 6 is presented which is designed to receive an article 7, as for instance, a bottle of perfume. This bottle has been shown square in cross section because this shape produces 55 a nice appearance and also prevents waste

of space. The ribbon, tape or other flexible member 8 is connected in any suitable manner to the lid 9 or to the edge of the container 1, said tape or other member extending beneath the article 7 as shown in Figure 2 and an appreciable distance over the false bottom 5, whereby it may be readily grasped and pulled for removing the article 7.

Arranged on the false bottom 5, are two 60 arc-shaped members 10 and 11, said members being connected by a brace 12, said arc-shaped members co-acting with the false bottom 5 and the side walls of the container 1 for supporting pan-shaped members 13 and 14 which are adapted to contain powder 65 or other cosmetics. On the powder or cosmetics just mentioned, are preferably placed powder puffs 15 and 16. If preferred, instead of using compacts having pans 13 and 14, an ordinary compact or solid block of powder could be mounted on the false bottom 5 and held in place by the arc-shaped members 10 and 11. The arc-shaped members 10 and 11 are so positioned that when 70 the compacts are in position as shown in Figures 1 and 2, there is a space or chamber 75 for receiving the lipstick container 18.

It will be noted particularly from Figure 1, that the various articles used as cosmetics are exposed to view as soon as the lid 9 is 80 opened and the articles in the drawer 3 are exposed only when said drawer is opened more or less. In order to make the vanity case complete, a mirror 19 is arranged in 85 the lid 9 so that when the lid is opened for exposing the cosmetics, the mirror will be automatically moved to a position for giving the desired reflection of the face. In respect to the drawer 3, it will be noted that 90 the same is provided with a shoulder 20 on each side which strike against the walls of the container 1 adjacent the cut-away portion 2 whereby the inward movement of the drawer is limited so that the outer contour 100 of the drawer may be made to match the front and side walls of the casing 1 so as to give a neat appearance to the container.

What I claim is:—

1. A vanity case, comprising a container 105 having the lower front part cut away, a drawer fitted into the bottom of said container formed with front and side walls conforming to the front and part of the side walls of the container so that when the 110

- drawer is closed a continuous wall surface will be presented, said drawer having slightly offset end walls, said end walls being offset sufficiently to permit the drawer 5 to fit between the end walls of the container, means for supporting cosmetics in the upper part of the container, and a lid hinged to said container for closing the container.
10. 2. A vanity case, comprising a container, a lid for the container, means for dividing the container into a shallow chamber and a deep chamber, means for dividing the shallow chamber into a plurality of article receiving compartments, and a drawer mount- 15 ed in the container beneath the shallow chamber, the front of the drawer and part of the sides thereof being flush with the outside of the container.
3. A vanity case, comprising a container, a lid for the container, means for dividing the container into a shallow chamber and a deep chamber, means for dividing the shallow chamber into a plurality of article receiving compartments, and a drawer mounted 20 in the container beneath the shallow chamber, said drawer engaging the interior surface of the side wall of said container and being guided thereby.

CORNELIUS HENRY De BERNARDI.
